UNITED STATES PATENT OFFICE

FREDERICK E. HOLLINS, OF WINCHESTER, MASSACHUSETTS.

BURIAL-CASKET.

1,119,283.

Specification of Letters Patent. Patented Dec. 1, 1914.

Application filed September 10, 1914. Serial No. 861,033.

To all whom it may concern:

Be it known that I, FREDERICK E. HOLLINS, a citizen of the United States, and resident of Winchester, in the county of Middlesex and State of Massachusetts, have invented certain new and useful Improvements in Burial-Caskets, of which the following is a specification.

This invention relates to a burial casket 10 the bottom of which is provided, usually at the corners, with recesses, which expose portions of the casket wall for the purpose of forming grips or handles at the bottom portion of the casket, the recesses being of suitable size and shape to permit the insertion 15 of the fingers of persons carrying the casket.

The invention has for its object to provide improved means for covering or shielding said bottom recesses so that they will not 20 communicate with the interior of the casket, said covering or shielding means being preferably of such nature that the casket is materially strengthened thereby.

The invention consists in the improvements which I will now proceed to describe 25 and claim.

Of the accompanying drawings, Figure 1 represents a top plan view of one of the end portions of a casket embodying my invention. Fig. 2 represents a fragmentary perspective view showing a part of said end portion, the shield hereinafter described being represented by dotted lines. Fig. 3 represents a section on line 3—3 of Fig. 1. Fig. 4 represents a perspective view of the shield detached from the casket. Fig. 5 represents a section on line 5—5 of Fig. 4.

The same reference characters indicate the same parts in all the figures.

In the drawings, *a* represents the bottom, *b* one of the body ends, *c*—*c* the body sides and *d* the body corner piece of a casket of octagonal form. My invention, however, is not limited to a casket of such form and may 45 be applied to caskets otherwise formed.

It is customary to provide the bottom *a* with finger-receiving recesses *f* in suitable portions of its edges, usually at the corner portions, said recesses exposing the lower 50 edges of parts of the casket wall or body and, as here shown, the lower edges of the corner pieces *d*, so that said lower edges constitute grips or handles, the recesses *f* permitting insertion of the fingers through 55 the bottom *a*.

In carrying out my invention I provide

for each recess *f* a shield 12 which is preferably composed of a sheet metal blank to which the cupped or concavo-convex form represented by Figs. 3 and 4 is imparted by suitable dies. The base of the shield 12 is formed to fit the margin of the recess *f*, the shield projecting above the orifice and forming one side of a finger-receiving pocket 13. The shield constitutes a barrier 60 between the fingers inserted in said pocket and the storage space in the casket. The shield is provided with means whereby it may be attached to the casket, said means being preferably embodied in a flange 14 65 integral with the shield and adapted, in the embodiment of the invention here shown, to bear on the inner surface of the corner piece *d*, such flange having oblique wings 15 adapted to bear on the inner surfaces of the 70 head and side pieces *b* and *c*. Said flange and wings are perforated to receive attaching screws as represented by Fig. 4. The lower end of the shield is preferably provided with a horizontal flange 16 adapted to 75 bear on the under side of the bottom *a* to aid in supporting said bottom and preventing it from sagging.

The shield 12 constitutes a neat finish for the interior of the casket at the portions 80 where the recesses *f* are formed, concealing said recesses and preventing the upholstery or lining material within the casket from protruding through said recesses. The shield and its flanges constitute a reinforcing member or part which materially adds 85 to the strength of the casket, particularly at the corner portions thereof.

My invention is not limited to the form of the shield and its attaching means here 90 shown and the same may be variously modified without departing from the spirit of the invention.

Having described my invention, I claim:

1. A casket provided with a finger-receiving recess in the edge of its bottom exposing a portion of the lower edge of the wall of the casket, said portion forming a concealed handle, and a concealed cupped shield covering said recess and constituting one side of 100 a finger-receiving pocket within the casket and at the inner side of said handle, said shield having concealed attaching means engaged with the casket.

2. A casket provided with a finger-receiving recess in the edge of its bottom exposing a portion of the lower edge of the wall of 110

the casket, and a shield attached to the casket and formed to cover said recess and constitute one side of a finger-receiving pocket, said shield having a bottom-supporting flange engaged with the bottom of the casket.

3. As an article of manufacture a cupped shield formed to cover a recess in the edge of a casket bottom and to constitute one side of a concealed finger-receiving pocket, said shield having means engaging the interior of the casket for attachment thereto.

4. As an article of manufacture a shield

formed to cover a recess in a casket bottom and to constitute one side of a finger-receiving pocket, said shield having means for attachment to a casket, and a bottom-supporting flange adapted to engage the casket bottom.

In testimony whereof I have affixed my signature, in presence of two witnesses.

FRED. E. HOLLINS.
